**FLUSH HOOK FOR ATTACHMENT OF A LINE TO
A PANEL OR THE LIKE**

Carl J. Swendsen, Nevada City, Calif., assignor to Swendsen Engineering, Nevada City, Nev., a partnership of California

Filed June 22, 1964, Ser. No. 80,500

Term of patent 14 years

(Cl. D54—11)

FIG. 1

3—

FIG. 2

3—

FIG. 3

FIG. 1 is a side elevational view of a flush hook for attachment of a line to a panel or the like showing my new design.

FIG. 2 is a top plan view thereof.

FIG. 3 is a sectional view taken along line 3—3 of FIG. 2.

I claim:

The ornamental design for a flush hook for attachment of a line to a panel or the like, as shown.
